CLAIM

The ornamental design for a dessert base, as shown and described.

DESCRIPTION

FIG. 1 is a perspective view of a dessert base;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof, shown in an environment of use.

The broken lines shown in FIGS. 1–6 illustrate portions of the dessert base that form no part of the claimed design. The broken lines illustrating the fruit and whipped cream toppings in FIG. 8 are environment, while the remaining broken lines in FIG. 8 illustrate portions of the dessert base that form no part of the claimed design.
